UNITED STATES PATENT OFFICE.

EMMETT F. KAMMER, OF TACOMA, WASHINGTON.

ROADWAY.

1,166,051.

Specification of Letters Patent. Patented Dec. 28, 1915.

Application filed May 17, 1915. Serial No. 28,654.

To all whom it may concern:

Be it known that I, EMMETT F. KAMMER, a citizen of the United States, residing at Tacoma, in the county of Pierce and State 5 of Washington, have invented certain new and useful Improvements in Roadways, of which the following is a specification.

This invention has relation to roadways, pavements and the like, the purpose being 10 the provision of a roadway which will maintain the surface without sinking and which may be repaired at a comparatively small cost.

The invention consists of a roadway or 15 pavement having a metallic base which is provided upon its upper side with a confining rim or flange, and surfacing material placed upon the base and within the confining flange or rim.

20 A further purpose of the invention is the provision of a roadway particularly adapted for such thoroughfares provided with car-tracks, whereby a proper road surface is maintained between the rails and a proper 25 distance at the sides of the track.

With these and other objects in view, which will readily appear as the nature of 30 the invention is better understood, the same consists in the improved construction and 35 novel arrangement and combination of parts which will be hereinafter fully described and particularly claimed.

In the accompanying drawings has been 35 illustrated a simple and preferred form of the invention, it being, however, understood that no limitation is necessarily made to the precise structural details therein exhibited, but that changes, alterations and modifications within the scope of the invention as 40 claimed may be resorted to when desired.

Referring to the drawings:—Figure 1 is a transverse section of a roadway embodying the invention; and Fig. 2 is a top plan view thereof.

45 Corresponding and like parts are referred to in the following description and indicated in all the views of the accompanying drawings by the same reference characters.

In accordance with the invention, a base 50 is provided and placed upon a suitably prepared bed, such base being formed upon its upper side with a rim or flange which encloses a space in which surfacing material of any nature is placed. The base may be 55 provided in any number of sections but the several sections are substantially the same

in construction. The provision of the base in sections is a matter of convenience of handling and constructing. As indicated in the drawings, the base comprises a middle 60 section 1 and side sections 2 and 3. The middle section 1 is approximately square, whereas the side sections are oblong, but the several sections are of similar formation, each consisting of a base and an upstanding 65 rim or flange 4 which incloses a space in which paving material 5 of any nature is filled. It is not necessary that the base be of uniform thickness throughout its extent and, as indicated, the lower side of the base 70 is hollow thereby enabling the same to be constructed of a minimum amount of metal.

The bed upon which the roadway is constructed may be of any formation and, inasmuch as the invention is illustrated in connection with a roadway provided with a car-track, the bed is shown as consisting of cross ties 6 which are placed upon a properly prepared and graded surface, such ties receiving the rails 7 comprising the track and 80 furthermore supporting the several sections comprising the base. The edges of the sections comprising the base and bordering upon the rails 7 are made to conform to the outline of such rails, as indicated most 85 clearly in Fig. 1. It will thus be understood that, should occasion require, any one of the sections may be removed or replaced without making it necessary to disturb the rails 7. The middle section 1 is of greater 90 transverse span than the side sections 2 and 3 and corresponds to the distance between the rails 7. The side sections 2 and 3 are of a width corresponding to the amount of 95 roadway to be maintained at the sides of a car-track. The roadway along each side of the track bordering upon the strips to be maintained by the car company may be of any ordinary construction, depending upon the nature of the pavement preferred. In 100 order that the side sections may be properly supported, certain ties 6 are of a length so as to project the full width below the side sections, as indicated most clearly in Fig. 2.

When constructing a roadway in accordance with the invention, the base is placed in position, after which the space inclosed by the upstanding rim or flange 4 is filled with paving material 5 such as concrete. The paving material may be of any thickness and the upper surface may be arched or flat. The paving material 5 serves to weight 110

the base and thereby assists materially in retaining the same in place without requiring fastening means of any nature. The paving material 5 also serves to sustain the wear. 5 As indicated most clearly in Fig. 1, the edge portions of the sections bordering upon the rails are constructed to overlap the flanges of the rails and thereby assist materially in holding the rails in position against vertical 10 or lateral displacement.

It will be understood from the foregoing, taken in connection with the accompanying drawings, that the invention provides a roadway particularly adapted for thoroughfares provided with street car-tracks and admits of a proper surface being maintained at a nominal cost, since the metal itself prevents the surface from sinking and preserves a practically level surface under all conditions and, moreover, the surface is of such a nature as to admit of repairs to the track being made quickly and at a nominal cost. 20

While it is preferred to construct the base of metal it is to be understood that such base may be formed of any suitable material 25

and that the upper side is formed with a recess to receive filling material of any nature.

Having thus described the invention, what is claimed as new is:

1. In roadway construction, a base having its upper surface provided with a circumscribing rim or flange and having its lower side made hollow and thickened near its outer edges, and paving material filled into the space defined by the circumscribing flange. 30

2. In a roadway provided with a car-track, a base supported upon the bed receiving the rails of the track, said base embodying a middle and side sections of similar formation, the edge portions of the sections adjacent the rails conforming thereto and overlapping the base flanges of the rails, the several sections being formed upon their upper sides with circumscribing flanges, and paving material filled into the space defined by said flanges. 40

45 In testimony whereof I affix my signature.

EMMETT F. KAMMER. [L.S.]
